(57) **CLAIM**

The ornamental design for a mobile phone, as shown and described.

DESCRIPTION

FIG. 1 is a front perspective view of a mobile phone of the present invention;

FIG. 2 is a front view of the invention illustrated in FIG. 1; FIG. 3 is a rear perspective view of the invention illustrated in FIG. 1;

FIG. 4 is a rear view of the invention illustrated in FIG. 1; FIG. 5 is a top plan view of the invention illustrated in FIG. 1;

FIG. 6 is a bottom plan view of the invention illustrated in FIG. 1;

FIG. 7 is a right side view of the invention illustrated in FIG. 1; and,

FIG. 8 is a left side view of the invention illustrated in FIG. 1.

The broken lines shown in the views are included for the purpose of illustrating environment and portions of the mobile phone that form no part of the claimed design.

1 Claim, 7 Drawing Sheets
